UNITED STATES PATENT OFFICE

2,121,639

HOT WATER HEATING CONTROL DEVICE

Walter O. Lum, West Caldwell, N. J., assignor to
General Electric Company, a corporation of
New York

Original application July 6, 1933, Serial No.
679,172. Divided and this application March
24, 1936, Serial No. 70,603

2 Claims. (Cl. 103—87)

This application is a division of my prior application, Serial No. 679,172, filed July 6, 1933, and relating to heating systems.

The present invention relates to an improved form of hot water heating control device, particularly adapted for use in thermostatically controlled hot water house heating systems, although the invention is not necessarily limited thereto.

The principal object is to provide an improved form of electrically operated circulation control unit especially constructed for connection into the supply main of a hot water heating system for insuring positive and rapid circulation of the hot water when heating is required and for preventing circulation when heating is not required.

It is a further object to provide an improved form of hot water circulation control unit which may be electrically operated under the control of a thermostatic switch and arranged to give quiet, efficient and trouble free operation.

Another object is to provide such an electrically operated circulation control means in which the rate of circulation can be readily adjusted or controlled.

In the preferred embodiment of the present invention, a tubular housing unit is provided with flanges at the ends thereof for facilitating connection into the hot water piping system. The housing unit is specially formed to combine a circulation check valve and electric motor driven impeller pump for controlling the hot water circulation therethrough. The various advantageous features will be more fully understood from the following description of the accompanying drawing illustrating the preferred embodiment thereof. Fig. 1 shows the improved hot water circulation control device of the present invention connected in a hot water heating system of the improved type disclosed in my above mentioned prior application. Fig. 2 is a cross-sectional view showing the detailed construction of the improved control unit and Fig. 3 is a perspective view showing the form of the pump impeller.

In the hot water heating system shown diagrammatically in Fig. 1, the hot water is circulated through the room heating radiator 10 from the hot water oil burner boiler furnace 11. The boiler furnace 11 is shown as of the type described and claimed in Patent 1,995,185 although the present invention may be used with any other type of hot water boiler furnace desired. The improved hot water circulation control device 12 is connected in the pipe main 13 of the heating system extending from the top of the boiler furnace 11. The circulation control

unit 12 is operated by means of the electric motor 17 under the control of the room thermostatic switch 14.

The improved construction of the flow control unit 12 is shown in Fig. 2. The tubular casing 20 is formed to house the check valve 21 and the impeller pump 22 with the operating motor 17 resiliently suspended from the casing 20 and yieldingly connected to drive the impeller pump 22. The casing 20 is provided with the flanges 23 at the end thereof so that the control unit may be readily mounted by means of the cooperating flanges 24 in the hot water pipe main 13. This permits the flow control unit to be easily removed for inspection or repair or another unit substituted therefor without seriously disturbing the pipe connections.

The check valve 21 operates about the pivot 25 in cooperating relation with the valve seat 26 which is preferably mounted at an angle in the tubular casing 20, as shown. A restricted air bleeder passage 27 permits air entrapped in the hot water system to pass when the check valve 21 is closed. The petcock 28 is provided for releasing the entrapped air from the system. The removable cover plate 29 provides access to the check valve 21 and carries the adjustable stop 30 which determines the extent to which the check valve 21 may be opened and hence the rate of circulation through the hot water system.

The tubular casing 20 is provided with an inner dividing wall 35 extending substantially longitudinally and horizontally of the casing and provided with the opening 36 therethrough for forming the inlet of the impeller pump housing. 35 The impeller 22 of the pump, as more clearly shown in Fig. 3, is provided with a hub 37 for mounting upon the upper end of the pump shaft 38 and has the three pump blades 39 joined at their lower sides to the annular shroud 40. The water passes upwardly through the central opening formed in the shroud 40 and is forced out radially by the blades 39. A restricted air bleeder passage 41 prevents accumulation of air in the pump housing. 45

A support or bearing bracket 45 carries the end thrust bushings 46 for the pump shaft 38. This bushing bracket together with the motor support 47 are fastened to the casing 20 by means of the bolts 48. To hold the pump impeller 22 in position and provide a water-tight seal for the shaft 38, a yielding bellows member 50 is joined to a sealing end thrust washer 51. The spring 53 forces the sealing washer 51 against the bearing shoulder 54 mounted on the shaft 38 so as 55

to bias the shaft 38 vertically upwardly and thereby maintain the impeller 22 in proper operating position in its housing. This at the same time provides a water-tight seal so that any water 5 which may find its way into the interior of the bearing bracket 45 will be prevented from passing to the inside of the bellows member. A cap 55 is screwed on the bottom end of the support 45 to secure the bellows member 50 in place.

10 The electric driving motor 17 is resiliently suspended from the motor supporting bracket 47. For this purpose the motor is secured to a supporting ring 60 which has mounted thereon the studs 61. The motor may be removably mounted 15 on the floating ring 62 by having a bayonet slot connection between the ring 62 and the studs 61, for example, whereby the motor may be readily released from the floating ring 62. The floating ring 62 is supported by cushion members 20 having the resilient portions 63 fastened to elements 64 and 65 and held in place by the screw-threaded nuts 66 and 67. Thus one end of the resilient member 63 is supported by the motor support 47 and in turn supports the floating ring 25 62. This cushioned support prevents motor vibration from being transmitted to the heating piping system. The impeller pump preferably is driven through a flexible coupling 10 which is shown as of the type using resilient material interposed between solid material for taking up 30 torque variations to prevent transmission of noise and vibration to the heating system when the motor 17 is energized to operate the pump.

The flow control unit 12 is so connected in the 35 hot water pipe main 13 that thermal siphon circulation of the hot water tends to flow from left to right through the casing 20. Thus, it will be seen that the normal tendency is to maintain the check valve 21 closed when the pump is not being operated. The water is circulated through the 40 casing 20 from right to left when the impeller pump is operated, the check valve 21 opening in response to the pressure differential created by the pump.

45 The improved flow control device of the present invention may be operated in a heating system such as shown in Fig. 1 in the following manner although it may be used in other ways, if desired. When heat is called for by closing 50 of the room thermostat 14, the electromagnetic switch 15 is energized thereby completing the energizing circuit for both the water circulating motor 17 and the oil burner operating motor 71. This causes fuel to be supplied to the combustion 55 chamber of the furnace 11 and heat to be transferred from the products of combustion to the water in the boiler. The pump operates to circulate the hot water through the heating system in a direction counter to the normal thermosyphon flow of the heating medium. In case a 60 separate check valve 72 is used in the return line of the hot water heating system as shown in Fig. 1, it will be understood that the valve 72 is so connected as to open against its bias to permit circulation whenever the circulating pump 22 is 65 operated. When sufficient heat has been supplied by means of the radiator 16, the room thermostat 14 opens the energizing circuit of the electromagnetic switch 15 which in turn opens the

circuit to the circulator motor 17 and the oil burner motor 71.

In order that the water in the boiler furnace 7 may be always maintained at a high temperature to provide proper heating of the domestic 5 hot water heating coil 73 and to insure a reserve supply of heated water so that the hot water heating system can be supplied with hot water as soon as the pump is put into operation, a suitable thermostatic switch 74 is provided for separately starting operation of the oil burner motor 71 whenever the temperature of the water in the boiler furnace falls below a predetermined value. This is particularly advantageous in providing for an adequate supply of domestic hot 10 water both in summer and in winter even through the room thermostat 14 may not cause operation of either the water circulating motor 17 or the oil burner motor 71 during the summer time.

What I claim as new and desire to secure by 20 Letters Patent of the United States, is:

1. A control device for a hot water heating system comprising a horizontal tubular casing provided at each end with means for connecting the casing in the hot water piping system and having adjacent one end thereof a horizontally extending dividing wall with an opening therethrough opposite an opening in the bottom wall of the casing to form a centrifugal pump housing and adjacent the other end thereof a check valve 30 housing, a check valve movably mounted in said valve housing and biased to the closed position, a pump shaft having a bearing bracket mounted in and sealing the opening in the bottom wall of said casing and provided with spring thrust 35 bearing sealing means biasing the shaft vertically upward into said casing in predetermined alignment with said opening in said dividing wall, an impeller mounted on the upper end of said shaft for forcing circulation of the hot water 40 through said opening to open said valve against its bias, a motor supporting bracket mounted on said bearing bracket and extending downwardly from said bearing bracket, and an electric motor suspended from said support and connected with 45 the lower end of said shaft for driving said impeller.

2. A circulation control unit for a hot water heating system comprising a horizontal tubular casing having a centrifugal pump housing with 50 a vertical axis formed inside one end thereof and a check valve housing formed inside the other end thereof, a check valve mounted in said valve housing and biased to closed position for preventing passage of hot water through said casing, an impeller mounted in said pump housing, an electric motor mounted on said casing and connected to drive said impeller to force circulation of water through said casing to open said check valve against its bias, and means comprising 55 a pair of restricted air bleeder passages extending inside said casing and adjacent the upper wall thereof, one through said pump housing and the other through said check valve housing for passing air through said casing independently 60 of the operation of said impeller and said check valve.
